UNITED STATES PATENT OFFICE.

EBENEZER F. GRIFFITHS, OF PHILADELPHIA, PENNSYLVANIA.

PREPAYMENT GAS-METER.

SPECIFICATION forming part of Letters Patent No. 603,079, dated April 26, 1898.

Application filed October 13, 1897. Serial No. 655,041. (No model.)

To all whom it may concern:

Be it known that I, EBENEZER F. GRIFFITHS, a subject of the Queen of Great Britain, residing at Philadelphia, in the county of Philadelphia and State of Pennsylvania, have invented certain new and useful Improvements in Prepayment Gas-Meters, of which the following is a specification, reference being had therein to the accompanying drawings.

10 My invention relates to prepayment-movements to be attached to gas-meters.

My invention refers particularly to the mechanism controlling and operating the valve through which the gas is admitted into 15 the meter.

The object of my improvement is to simplify the mechanism controlling the gas-inlet valve and make it more positive and less likely to stick and jam by reason of any carelessness on the part of the operator.

In the accompanying drawings, Figure 1 is a plan view of the top of a meter having my improvement thereon, the cover of the meter being removed. Fig. 2 is a lengthwise sectional

25 view through the valve-controlling mechanism on line $x-x$ of Fig. 1. Fig. 3 is a sectional view on line $y-y$ of Fig. 1. Fig. 4 is a vertical sectional view through the valve, valve-box, and gas-inlet pipe. Figs. 5 and 6 30 are detailed views of the cams operating the gas-inlet valve. Fig. 7 shows a modified form of valve and the lever operating same.

A represents the outer casing or body of the meter. A' is the gas-inlet pipe, connecting with the street-main, and A² the gas-outlet, connecting with the pipes in the house.

B is the coin-box, attached to the side of the meter near the inlet-pipe and provided with a suitable coin-slot on the top thereof.

40 B is the valve box or inclosure, surrounding the valve on all sides and having in the bottom thereof the opening a, through which the gas is admitted from the pipe A', flowing in the direction indicated by the arrows 45 through the short pipe a'.

a² is a puppet-valve located on the bottom of the valve-box and connected with the gas-pipe passing into the meter.

a³ is the stem of the valve and has thereon 50 two small disks 1 1, located a short distance

apart, so as to form stops for the ends of the forked arm or lever a⁴, attached to the cylindrical shaft a⁵ in the side of the valve-box.

a⁶ is a stuffing-box surrounding the shaft a⁵, thus preventing the gas escaping into the 55 other parts of the meter.

b, b', b², and b³ are the various levers operated by the vertical shafts b⁴ and b⁵, that connect with the bellows inside of the meter.

b⁶ is the vertical crank-shaft, extending to 60 and operating the valves in the gas-meter.

b⁷ is a horizontal shaft extending from the vertical crank-shaft b⁶ to and operating the usual form of dial mechanism on the front of 65 the meter.

b⁸ is a worm-wheel on the inner end of the shaft a⁷ and engaging with the worm b⁷ on the end of the crank-shaft b⁶.

c is a screw-threaded shaft having one end secured in a suitable bearing formed in the 70 support c', the opposite end fitting into a cylindrical opening formed in the square shaft d, that has a suitable bearing in the support c'.

c³ is a worm-wheel on the screw-threaded 75 shaft c and engaging with the worm d⁴ on the shaft a⁷.

d' is a hollow cylindrical rack, one end of which fits over and slides upon the shaft d, the opposite end being internally screw-threaded to fit over the screw-shaft c.

d² is a shaft supported below and at right angles to the hollow cylindrical rack d', and has thereon the spur gear-wheel d³, that engages with the cylindrical rack d'.

e is a disk secured on the shaft d² and having at one point in its circumference a cam-notch e² and an extended lip or projection e' at one side of said notch.

f is an oscillating finger having a concave 90 portion f² fitting over and riding upon the periphery of the disk e. The concaved portion of the finger f is held up to and in sliding contact with the periphery of the disk e by reason of the projection f', the outer end 95 of which extends just beyond a line connecting the centers of the shafts upon which the two parts e and f are mounted.

f² is the shaft supporting the finger f.

g is a crank fitting on the inner end of the 100

shaft f^2 and having an extending arm g' , that fits between the forks of the arm or lever g^2 on the shaft a^5 , that extends into the valve-box and carries the forked arm or lever a^4 , that operates the valve a^2 .

In place of the forked arm a^4 and the valve-stem a^3 the plain arm a_4 and the link a_3 (shown in Fig. 7) may be used, if desired.

The dial upon which is registered the quantity of gas for which coins have been placed in the coin-box B is located on the outside of the meter, and a hand or pointer secured on the outer end of the shaft d^2 passes around and over it.

15 g^3 is a projection formed on the end of the cylindrical rack d' . This projection impinges against a corresponding projection g^4 on the top of the support g^5 , that carries one end of the shaft f^2 and forms a positive stop for the cylindrical rack when it has been moved the full distance required, thus preventing the rear end of said rack from being jammed up against the spur gear-wheel c^3 on the end of the screw-threaded shaft c .

20 25 The knob or handle B² for starting the mechanism after the coin has been placed in the coin-slot is connected by suitable operating mechanism with the end of the square shaft d in any suitable manner.

30 When the cylindrical rack d' is in the position shown in Figs. 1 and 2, the outer end of said rack is up against the inside of the support c^2 and the valve a^2 just closed. To open the valve a^2 , the shaft d is turned so as to screw the cylindrical rack up on the screw-threaded shaft c toward the support c' .

35 This movement of the rack d' will turn the spur gear-wheel d^3 , moving the shaft d^2 , turning the disk e , and imparting a quick movement 40 to the finger f , turning the shaft f^2 , crank g , and arm g' , thus imparting a movement to the forked arm g^2 , moving the shaft a^5 , and forked arm a^4 , which, operating upon the valve-stem a^3 , raises the valve a^2 .

45 To close the valve a^2 , the movement of the several parts is in the opposite direction, which movement is caused by the flow of gas through the meter operating the crank-shaft b^6 , worm b^7 , worm-wheel a^8 , and shaft a^7 . The cylindrical rack d' being 50 back against the support c^2 when the valve a^2 is closed and the stop g^3 impinging against the extension g^4 on the support g^5 when the valve is open, it is impossible to jam the parts or strain the valve-connections, no matter how carelessly the device is operated.

55 That part of the periphery of the disk e that comes in contact with the concave part of the finger f being the arc of a circle, no motion is imparted to the valve mechanism, except 60 when the projecting lip e' impinges against the lip f' or the rear side of the notch e^2 operates against said lip f' .

By the construction of the valve-operating mechanism shown I am enabled to quickly 65 open the valve to the fullest extent and hold

it in that position until almost all of the gas paid for has been consumed and the cylindrical rack d' has traversed nearly the whole length of the screw c .

Having thus described my invention, what I claim as new, and desire to secure by Letters Patent, is—

1. In a prepayment gas-meter, the combination of the disk e , notch e^2 and lip or extension e' thereon adjacent to said notch, mounted on a shaft and connected with mechanism for turning, with the oscillating finger f , provided with a concaved bearing-surface f^3 adapted to fit and rest upon the periphery of the disk e , and a finger or extension f' located at one end of said concaved portion, and adapted to enter the notch e^2 in the disk e to instantly close the valve a^2 to which it is suitably connected, as set forth. 75

2. In a prepayment gas-meter, the combination of the disk e , having a suitable notch e^2 therein, and mounted on a suitable shaft and connected with mechanism for turning; with the oscillating finger f having a bearing-surface f^3 and a lip or extension f' at one end of the said bearing-surface, said finger being secured upon a shaft and connected with means for imparting movement to the valve-operating mechanism, the disk e sliding in the bearing-surface f^3 to hold the valve positively 90 open and the lip f' entering the notch e^2 to instantly close the said valve, as set forth. 95

3. In a prepayment gas-meter, the disk e , shaft d^2 , spur-wheel d^3 , cylindrical rack d' , having on the end thereof the stop g^3 , in combination with the oscillating finger f , having thereon the extending lip f' , support g^5 , having thereon the projection g^4 , against which the pin or projection g^3 , will impinge, and the shaft f^2 , connected with mechanism for opening and closing the valve a^2 , substantially as shown and described. 105

4. In a prepayment gas-meter, the combination of the disk e , having thereon the extending lip e' , mounted on a shaft and connected with mechanism for turning the same, with the oscillating finger f , having thereon the lip or extension f' , the shaft f^2 , suitably supported and having on one end thereof the crank g , and arm g' , fitting into the forked 110 arm or lever g^2 , the shaft a^5 , forked lever a^4 , and valve a^2 , having the extending valve-stem a^3 , fitting into the arm a^4 , and provided with the stop 111, substantially as shown and described. 115

5. In a prepayment gas-meter the disk e mounted on a shaft and having in the periphery thereof a notch e^2 , an extended lip or projection e' to one side thereof and connected with suitable mechanism for turning, in combination with the oscillating finger f , mounted on a shaft and having the two ends thereof in contact with and resting upon the periphery of the disk e and lying upon opposite sides of a line joining the centers of said shafts, 120 125 130

said finger being mounted on a shaft and connected with means for imparting movement to the valve-operating mechanism, as set forth.

6. In a prepayment gas-meter the combination of the disk *e*, mounted on a shaft and connected with suitable mechanism for turning, with the oscillating finger *f* mounted on a shaft and having the two ends thereof in contact with and resting upon the periphery of the disk *e* and lying upon opposite sides of

a line joining the centers of said shafts, said finger being mounted on a shaft and connected with means for imparting movement to the valve-operating mechanism, as set forth.

In testimony whereof I affix my signature ¹⁵ in presence of two witnesses.
